United States Patent Office

Des. 176,624
Patented Jan. 10, 1956

176,624

COMBINE CAB

Lawrie G. McIntosh, Toronto, Ontario, Canada, assignor
to Massey-Harris-Ferguson, Inc., Racine, Wis., a cor-
poration of Maryland

Application April 18, 1955, Serial No. 35,554

Term of patent 14 years

(Cl. D14--3)

Fig. 2

Fig. 4

Fig. 3

Figure 1 is a right side elevational view of a combine cab embodying my new design.

Figure 2 is a front elevational view of the cab shown in Figure 1.

Figure 3 is a perspective view, on an enlarged scale, of the cab shown in Figures 1 and 2.

Figure 4 is a right side elevational view, on an enlarged scale, showing the cab of Figure 1 with the top down.

The combine illustrated by means of broken lines is shown for purposes of illustration.

I claim:

The ornamental design for a combine cab, substantially as shown and described.
